UNITED STATES PATENT OFFICE.

THOMAS C. MORRIS, OF LITTLE ROCK, ARKANSAS.

DRYING-KILN.

No. 901,811.

Specification of Letters Patent.

Patented Oct. 20, 1908.

Application filed May 11, 1908. Serial No. 432,218.

To all whom it may concern:

Be it known that I, THOMAS C. MORRIS, a citizen of the United States, residing at Little Rock, in the county of Pulaski and State of Arkansas, have invented certain new and useful Improvements in Drying-Kilns, of which the following is a specification.

This invention appertains to that class of drying kilns which are designed particularly for drying various kinds of lumber, and involves advantageous improvements, the nature of which will be pointed out more fully hereinafter.

For a full understanding of the invention, reference is to be had to the following detail description and to the accompanying drawings, in which

Figure 1 is a vertical longitudinal sectional view showing a kiln constructed in accordance with the invention; Fig. 2 is a transverse sectional view; Fig. 3 is a top plan view; Fig. 4 is a detail view bringing out more clearly the supporting hangers for the steam pipes; Fig. 5 is a view embodying modified means for supporting the steam pipes.

Throughout the following detail description and on the several figures of the drawings similar parts are referred to by like reference characters.

Specifically describing the construction of the invention, and referring to the drawings, the numeral 1 designates the side walls of the kiln, the numeral 2 the rear wall, and the numeral 3 the front wall.

4 indicates the top of the kiln.

Supported longitudinally in the kiln are the rails 5 upon which the cars of lumber are supported when the lumber is being dried in the customary manner.

The front wall 3 of the kiln is provided with suitable doors 6 which are adapted to be opened in the usual way when the cars of lumber are being moved into or out of the kiln.

In the practical embodiment of the present invention a plurality of kilns will be arranged side by side but the detail construction of all of the kilns being the same, one only will be described.

The drying means employed in this invention comprises an important feature thereof, being designed especially to increase the efficiency of the kiln in drying lumber, and furthermore, to admit of controlling the de-

gree of heat in the kiln more effectively than is admissible in the various types of kilns at present most commonly in use.

Arranged beneath the rails 5 and extending transversely across the kiln at suitable intervals are a plurality of cross bars 7, made preferably from channel iron, the ends of which are seated in the walls 1 of the kiln, the intermediate portions of which are connected with vertical I-beams 8 upon the upper ends of which are supported and secured the rails 5. The lower end of each beam 8 is carried by a suitable foundation 9 and at intervals certain of the beams are connected together by means of rods and turn-buckles for the purpose of rigidity.

Carried by the cross bars 7 are a plurality of hangers 11 in each of which are supported a series of steam pipes 12. Each hanger 11 is composed of spaced plates connected at the upper ends by a bolt 11^a, and a stirrup 13 receiving the adjacent cross bars 7 is connected with the upper end of each hanger 11, attaching the same to the cross bar in a substantial manner. Transverse bolts 14 connect the spaced plates of each hanger 11, and the pipes 12 are supported upon the bolts 14 as shown more clearly in the drawings. Four series or sets of steam pipes 12 are preferably provided for each kiln and each set of pipes is vertically arranged and inclines slightly downward toward the rear wall 2 of the kiln. The rear ends of each set of pipes 12 are connected with a rear header 15 while the front ends of such set of devices are connected with a front header 16. Leading from the lower end of each rear header 15 is a drain pipe 17 which is arranged substantially in vertical alinement with the adjacent set of steam pipes 12, and which extends through the front wall 3 of the kiln to a suitable point of discharge for the water of condensation finally passing to the header 15 from the pipes 12.

Steam is used as a heating medium for the kiln and is admitted to each set of steam pipes 12 from a steam supply pipe 18 having a suitable valve 19, whereby the steam supply may be cut off when desired. Leading from the steam supply pipe 18 is an upwardly extending branch supply pipe 20 and a downwardly extending branch pipe 21, the pipes 20 and 21 for each steam supply pipe 18 being connected with one of the headers 16 and passing through the front wall 3 of the kiln for this purpose. Suitable venti-

lating flues 22 are provided in the walls of the kiln to permit the steam or moisture rising from the lumber as it dries to pass out of the kiln.

5 In Fig. 5 is shown a modified form of supporting means for the various sets of steam pipes in the kiln. In this construction the hangers 11 are not employed, but spaced supporting plates 23 are used, the lower ends 10 of said plates being seated in a suitable foundation of concrete while the upper ends are attached to the cross bars 7. The plates 23, however, are connected by the bolts 24 which perform the same function as the bolts 15 14, before described, in supporting the pipes 12 of the series carried by the plates or members 23.

It will be understood that any number of series of steam pipes may be arranged in 20 each kiln, within the contemplation of the invention. The practical disposition of the pipes 12 of each series is particularly advantageous because water of condensation in the feed or steam supply pipe 18 will pass to the 25 lower end of the front header 16 by the branch pipe 21, and does not mix with the dry steam passing outwardly through the branch pipe 20 to the upper portion of the header 16. The water of condensation is 30 thus separated from the dry steam, so to speak, as the steam is fed to each series of steam pipes 12 from the feed pipe 18 connected therewith. The water of condensation drains from the rear header 15 of each 35 series of steam pipes 12 by means of the drain pipe 17 before described. Attention is directed to the fact that the water of condensation passing from each feed or supply pipe 18 to the lower portion of the connected 40 series of pipes 12 heats the lowermost pipes of said series and the heat rising from said

pipes heats the pipes 12 above the same. The uppermost pipes of each series being thus heated, those pipes nearest to the lumber supported above the series will contain only 45 dry steam which is of great advantage in drying apparatus of the type to which the present invention relates. The temperature in the kiln may be increased by reason of the above advantageous arrangements of steam 50 pipes to a high degree and this is of great importance in drying kilns of this type. Should it be desired to dry cypress or hard woods one or more of the valves 19 may be operated so as to cut off the supply of steam 55 to the connected series of steam pipes 12 until the desired temperature is secured. In this manner all kinds of lumber may be dried, as will be readily appreciated.

Having thus described the invention, what 60 is claimed as new, is:

A dry kiln of the class described embodying side, front, and rear walls, rails extending longitudinally of the kiln but supported in the front and rear walls thereof, vertical 65 I-beams arranged at intervals in the length of the kiln and supporting upon the upper ends thereof the said rails, cross bars having opposite ends seated in the side walls of the kiln and secured intermediate of their ends 70 to the I-beams, supporting members connected at their upper ends with the cross bars, heating apparatus carried by said supporting members, and brace means connecting the I-beams substantially as described. 75

In testimony whereof I affix my signature in presence of two witnesses.

THOMAS C. MORRIS.
